UNITED STATES PATENT OFFICE.

LEWIS C. PACKER, OF SPRINGFIELD, MASSACHUSETTS, ASSIGNOR TO WESTINGHOUSE ELECTRIC & MANUFACTURING COMPANY, A CORPORATION OF PENNSYLVANIA.

MOUNTING FOR SEWING-MACHINE MOTORS.

Application filed February 10, 1921. Serial No. 446,365.

To all whom it may concern:

Be it known that I, LEWIS C. PACKER, a citizen of the United States, and a resident of Springfield, in the county of Hampden 5 and State of Massachusetts, have invented a new and useful Improvement in Mountings for Sewing-Machine Motors, of which the following is a specification.

My invention relates to machines, such 10 as sewing machines, that are equipped for operation by electric motors, and it has for its object to provide a structure wherein the machine and the motor are united in an improved manner to form a strong, 15 rugged, compact and inexpensive combination.

Briefly, my invention comprises mounting the motor upon a shaft which projects through, and is pivotally mounted in, the 20 head of the machine, and providing means within the head of the machine for retaining the driving pinion of the motor in yielding engagement with the hand wheel of the machine.

Heretofore, it has been customary to drive 25 a sewing machine by means of a motor so disposed on the machine table as to engage the hand wheel or by fastening the motor to the machine frame by means of a complicated and expensive supporting structure.

More specifically, my invention comprises supporting the motor by means of a stub shaft pivotally mounted in the head of the machine and having a casing member rigidly 30 mounted thereon which, in turn, embraces a portion of the motor. A spring is so disposed within the head of the machine as to bias the motor and thus maintain the driving pinion thereof in yielding engagement 35 with the hand wheel of the machine.

For a better understanding of my invention, reference may now be had to the accompanying drawings, of which Fig. 1 is a side elevational view of a portion of a 40 sewing-machine head provided with a motor constructed in accordance with my invention.

Fig. 2 is a cross-sectional view of the 45 structure illustrated in Fig. 1, the section being taken along the line II—II thereof.

Fig. 3 is a sectional view of a structure 50 shown in Figs. 1 and 2 and illustrating the means disposed within the machine head by which the motor is supported and biased to cause the motor pinion to engage the hand

wheel. The section is taken along the line 55 III—III of Fig. 2.

In the accompanying drawings, a sewing machine head 1 is shown as being provided with the usual shaft 2 and hand wheel 3. The head 1 comprises a substantially horizontally extending arm 4 and an upright standard 5, the central portion of which is indented, as shown at 6. The indented portion 6 is provided with a centrally disposed substantially circular opening 7. The 60 opposite side of the head member is provided with a relatively large opening 8 disposed in alignment with the opening 7.

An electric motor 9 is provided with an opening 10 in one side of the casing thereof, 70 which is closed by an auxiliary casing member 11, the central portion of which is provided with an opening 12. Rigidly disposed within the opening 12 is a stub shaft 13 which also extends into the opening 7 in the 75 head 1. The stub shaft 13 consists of a substantially cylindrical sleeve member 14 which engages the walls of the opening 7 and is provided, at its outer end, with a rigidly attached lever arm 15.

Within the sleeve member 14 is disposed a bolt 16, one end of which is provided with a locking washer 17 disposed between the head 18 of the bolt 16 and the auxiliary 80 casing member 11 of the motor 9, locking the sleeve 14 thereto. A nut 19 is mounted on the opposite end of the bolt 16 and serves to draw the locking washer 17 into intimate contact with the casing member 11. A coiled compression spring 20 is disposed 85 within the head member to engage a supporting member 21 and one end of the lever 15. The spring 20 tends to rotate the sleeve 14 with respect to the head member 1, thus causing the motor driving pinion to be held 90 in yielding engagement with the hand wheel 3 of the machine. The opening 8 in the head of the machine permits of ready assembly of the arm 15, the nut 19 and the spring 20 inside of the head member 1.

The motor 9 is provided with a shaft 22 having mounted thereon a pinion 23 which operatively engages the hand wheel 3. The spring 20 serves to bias the motor to hold the pinion 23 in engagement with the hand 95 wheel 3.

As the motor 9 is provided with flattened side portions and is attached to the head

in the indented portion 6, the overall width of the machine is increased but very little beyond the outer periphery of the hand wheel by the addition of the motor.

5 It will be apparent that, by mounting the motor in the manner shown, the motor will be pivoted by the spring 20 about an axis passing substantially through its center of gravity, thereby reducing the amount of 10 work imposed upon the spring. It will also be apparent that no portion of the motor projects within the head casing and that, by placing the spring 20, together with the other coacting portions, within the head, a 15 structure of good appearance, which is simple and inexpensive to manufacture may be readily produced.

While I have shown but one form of my 20 invention and have described in detail but a single application of the same, it will be obvious to those skilled in the art, that it is not so limited, but is susceptible of various minor modifications and changes without departing from the spirit thereof; and I desire, therefore, that only such limitations shall be placed thereupon as are imposed by the prior art or are specifically set forth in the appended claims.

I claim as my invention:

25 1. In combination, a sewing machine comprising a head having a hand wheel mounted thereon, an electric motor provided with a driving pinion disposed in engagement with said hand wheel, means for mounting said motor on said head comprising a stub shaft projecting into said head, said shaft being pivotally mounted in said head.

2. In combination, a sewing machine comprising a head having a hand wheel mounted thereon, an electric motor provided with a driving pinion, means for mounting said motor on said head comprising a stub shaft projecting into said head, and means disposed within said head for maintaining said driving pinion in yielding engagement with said hand wheel.

3. In combination, a sewing machine comprising a head having a hand wheel mount-

ed thereon, an electric motor provided with a driving pinion, means for mounting said motor on said head comprising a stub shaft projecting into said head, said shaft being pivotally mounted in said head, and resilient means disposed within said head for maintaining said driving pinion in engagement with said hand wheel.

4. In combination, a sewing machine comprising a head having a hand wheel mounted thereon, an electric motor provided with a driving pinion, means for mounting said motor on said head comprising a stub shaft projecting into said head, said shaft being pivotally mounted in said head and a spring disposed within said head for maintaining said driving pinion in engagement with said hand wheel.

5. In combination, a sewing machine comprising a head having a hand wheel mounted thereon, an electric motor provided with a driving pinion, means for mounting said motor on said head comprising a stub shaft projecting into said head, said shaft being pivotally mounted in said head, a lever arm mounted on said shaft within said head, and a spring attached to said lever arm tending to maintain said driving pinion in engagement with said hand wheel.

6. In combination, a dynamo-electric machine provided with a casing, a pin projecting into said casing, and means pivotally engaging said pin for supporting said motor and a spring associated with said engaging means tending to rotate said pin and said dynamo-electric machine with respect to said engaging means.

7. In combination, a sewing machine comprising a head, a dynamo-electric machine provided with a casing, a pin projecting into said machine head and into said casing for mounting said dynamo-electric machine on said head.

In testimony whereof, I have hereunto subscribed my name this fourth day of February 1921.

LEWIS C. PACKER.
